(57) **CLAIM**

The ornamental design for an installation frame for screen protector, as shown and described.

DESCRIPTION

FIG. 1 is a top perspective view of a first embodiment of the installation frame for screen protector in accordance with our invention;

FIG. 2 is a bottom perspective view hereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and

FIG. 8 is a rear elevation view thereof;

FIG. 9 is a top perspective view of second embodiment of the installation frame for screen protector in accordance with our invention;

FIG. 10 is a bottom perspective view thereof;

FIG. 11 is a top plan view thereof;

FIG. 12 is a bottom plan view thereof;

FIG. 13 is a right side elevation view thereof;

FIG. 14 is a left side elevation view thereof;

FIG. 15 is a front elevation view thereof; and,

FIG. 16 is a rear elevation view thereof.

The broken lines in FIGS. 1, 3-6, 9, 11, 13 and 14 represent features of the installation frame for screen protector that form no part of the claimed design.
